[57] ABSTRACT

An automatic rhythm device incorporated in an electronic musical instrument comprises as a conventional construction, a clock pulse oscillator, a multistage frequency dividing counter chain, a rhythm pattern pulse encoding matrix, rhythm selector switches, rhythm sound sources and a rhythm sound reproducing system arranged in the order mentioned; and as an additional construction, a normally nonconducting gate circuit coupled between the sound sources and the sound reproducing system and a rhythm start and stop controller which includes a two-way switch operated by a player during performance for an organ section of the instrument and a bistable circuit having two halves alternately brought to reverse positions by the operation of the switch thereby to produce a control signal for alternately starting or stopping the oscillation of the clock oscillator in response to the operation of the switch as well as for causing the gate circuit alternately to be conducting or non-conducting.

The device constituting a rhythm section for the musical instrument enables the start and termination of rhythm sounds without failure.

SHEET 2 OF 2

FIG. 2

AUTOMATIC RHYTHM DEVICE WITH START AND STOP CONTROLLER FOR CLOCK OSCILLATOR AND A GATE

BACKGROUND OF THE INVENTION

This invention relates to an automatic rhythm device incorporated in electronic musical instruments and more particularly to an improvement of the rhythm start and stop control arrangement.

Electronic electronic musical instruments such as electronic organs, have recently been more favorably accepted a then they include, in addition to the conventional organ section for playing ordinary musical sounds consisting of melody, chord or bass sounds or combinations thereof upon selective depression of a plurality of manual and/or pedal keys arranged in the order of musical notes, an automatic rhythm device constituting a rhythm section for playing rhythm sounds consisting of percussion instruments (e.g., claves, maracas, cymbals, bass drum and snare drum) or the tones of melody, chord or bass combinations thereof in exact timing with a rhythm pattern pre-selected from various rhythm patterns such as the march, rumba, samba, tango, waltz and bossa nova.

In such an electronic musical instrument, it is desirable to include a rhythm start and stop control arrangement so as to cause the initiation or start as well as the stop or termination of rhythm sounds of the rhythm section exactly according to manipulation by the musical instrument player.

Rhythm start and stop control arrangements for electronic musical instruments of the prior art include a conventional relay mechanism comprising a coil selectively energized by a two-way switch attached for lateral movement by a player's foot to an appropriate performance control member for the organ section, for example, a volume control expression pedal originally depressed by the player's foot during performance and a normally open switch closed by the energization of the coil so as to allow the generation of rhythm sounds from the rhythm section.

However, the rhythm start and stop control arrangement using the relay mechanism of the above mentioned construction had the drawback that the normally open switch which should be kept closed during rhythm performance was often unnecessarily opened by an external mechanical shock or vibration with the result, for example, that rhythm sounds from the rhythm section disappeared in the course of a performance. It is therefore the object of this invention to provide an automatic rhythm device incorporated in electronic musical instruments which provide positive control of the operation and non-operation of rhythm sounds from the rhythm section, and which device is unaffected by external mechanical shock.

SUMMARY OF THE INVENTION

The automatic rhythm device of the present invention is characterized in that it includes a normally non-conducting gate circuit coupled between the rhythm sound sources and the sound reproducing system, and a rhythm start and stop controller having a two-way switch alternately moved from one position to the other by a player during performance on the organ section and a bistable circuit which has two halves alternately brought to reverse positions by the two-way movement of the switch and either half output of which causes the

gate circuit to be alternately conducting or non-conducting as well as a clock oscillator for generating a repetitive basic tempo pulse train for the rhythm section to be alternately started or stopped.

The automatic rhythm device of this invention incorporated in an electronic musical instrument has the advantage that the start and termination of the rhythm sounds of the rhythm section are positively initiated or terminated and securely maintained in either state by operating the two-way switch at the start and termination of performance on the organ section, and the device is unaffected by external mechanical shocks since no mechanically contacting switch is used as in the relay mechanisms of the prior art.

BRIEF DESCRIPTION OF THE DRAWING

FIG. 1 shows a schematic block circuit diagram of an automatic rhythm device incorporated in an electronic musical instrument in accordance with the invention; and

FIG. 2 is a practical circuit arrangement of a circuit portion including a rhythm start and stop controller shown in FIG. 1.

PREFERRED EMBODIMENT OF THE INVENTION

FIG. 1 is a schematic block diagram of an automatic rhythm device incorporated in an electronic musical instrument embodying the invention.

Automatic rhythm devices of the prior art generally include a clock pulse oscillator 11 of the free-running oscillation type such as an astable multivibrator provided, for example, with a frequency control element 12. The clock oscillator 11 is designed to generate a repetitive basic tempo pulse train having a frequency or time width corresponding to the shortest beat unit (generally, a quaver or a semiquaver) required to produce the later described various sets of rhythm pattern pulses. Output pulses from the clock oscillator 11 are conducted to a multistage frequency dividing counter chain 13 which comprises, in this example, four stage flip-flops or binary counters 131, 132, 133 and 134 connected to each other in cascade. These binary counters 131 to 134 are operated with frequencies equal to one-half, one-fourth, one-eighth and one-sixteenth of that of output pulses from the clock oscillator 11 and are respectively provided with two output lines $a-\bar{a}$, $b-\bar{b}$, $c-\bar{c}$ and $d-\bar{d}$ each producing two output pulses indicating the binary ONE and ZERO which are different by 180° in phase. The output pulses from the binary counters 131 to 134 are conducted into a rhythm pattern pulse-encoding matrix 14 of the hereinafter described construction to be converted into various types of rhythm pattern pulse trains such as for waltz, march and rumba.

As is well known to those skilled in the art, the rhythm pattern pulse-encoding matrix 14 is ordinarily constructed of a diode matrix M arranged selectively to connect diodes D to the predetermined crosspoints of a plurality of column lines connected to the two output lines of the binary counters 131 to 134 respectively intersecting a plurality of row lines which are impressed with clock pulses from the clock oscillator 11; as is known in this field, as well as of AND logic and OR logic circuits each having inputs connected to the predetermined combination of the row lines.

Various sets of rhythm pattern pulse trains delivered from the AND and OR logic circuits in the encoding

matrix 14 pass through rhythm selector switches 15 selectively operated by a player prior to performance so as to be supplied as trigger signals to the preselected one or more of a plurality of rhythm sound sources $RH_1, RH_2 \dots RH_n$ such as those of the cymbals, maracas and claves. Rhythm sounds from the triggered rhythm sound source or sources are supplied to a sound reproducing system 16 including a volume controller VR, an amplifier A and a loudspeaker S so as to be made audible.

The automatic rhythm device of this invention incorporated in an electronic musical instrument is characterized in this that there are further provided a normally nonconducting gate circuit 17 connected between the rhythm sound sources RH_1 to RH_n and the sound reproducing system 16, and a rhythm start and stop controller 18 constructed as later described so as to alternately deliver a signal for rendering the gate circuit 17 conductive or non-conductive as well as for rendering the clock pulse oscillator 11 operative or non-operative through a pulse shaper 19 when there a reversing switch 20 of a normally open type is closed. Such switch may be attached, to an appropriate performance control member of the instrument, e.g., a volume control expression pedal 21 (permissibly a knee lever) usually manipulated by lateral movement of the player's right foot during a performance.

The rhythm start and stop controller 18 is further provided with a stand-by switch 22 having a movable contact 22a and two stationary contacts 22b and 22c, and a clamping switch 23 of a normally open type closed at the time when the manipulation of the switch 20 should be rendered non-effective.

FIG. 2 is a practical arrangement of a circuit portion including the rhythm start and stop controller 18 shown in FIG. 1.

The rhythm start and stop controller 18 comprises a stand-by circuit 30 which includes a stand-by switch 22 and a bistable circuit constructed of two grounded-emitter transistors Q_4 and Q_5 having their collectors connected via the corresponding resistors R_3 and R_4 to the power source terminal 32P as well as to the corresponding stationary contacts 22b and 22c of the switch 22, each of the transistors Q_4 and Q_5 having its base cross-coupled via the corresponding resistors R_5 and R_6 to the collector of the other transistor; a trigger signal source 31 which includes a grounded-emitter transistor Q_1 having its base connected via two series connected resistors R_1 and R_2 and the reversing switch 20 to a positive power source terminal 32P and rendered conductive when the switch 20 is closed; a flip-flop or bistable circuit 33 which includes two grounded-emitter transistors Q_2 and Q_3 each having its base cross-coupled to the collector of the other transistor via a parallel circuit of a resistor and a capacitor with the flip-flop state alternately reversed by an output from the trigger signal source 31, the clamping switch 23 being connected between the collector and emitter of the transistor Q_3 for clamping the reversible operation of the flip-flop 33; an initial condition-setting circuit 34 which includes a grounded-emitter transistor Q_6 having its collector-emitter path connected in parallel with that of the transistor Q_3 in the bistable circuit 33 and its base connected via a resistor R_7 and a forwardly biased diode D_1 to the power source terminal 32P as well as to the collector of the transistor Q_5 in the stand-by circuit 30 via a diode D_2 of the indicated polarity, the

movable contact 22a of the stand-by switch 22 being connected to the ground and contacting that one 22b of the two stationary contacts which is connected to the collector of the transistor Q_4 during the nonoperating period of the device; and a switching circuit 35 which includes a grounded-emitter transistor Q_7 having its base connected via a resistor R_8 to the collector of the transistor Q_6 as well as to the collector of the transistor Q_5 in the stand-by circuit via a resistor R_9 and its collector connected via a resistor R_{10} to the power source terminal 32P. The gate circuit 17 comprises a field effect transistor Q_8 having a conductivity type complementary to that of the transistors Q_1 to Q_7 used in the rhythm start and stop controller 18 and its gate connected to the collector of the transistor Q_7 , the drain-source path or conduction channel of the field effect transistor Q_8 being connected between the rhythm sound sources RH_1 to RH_n and the sound reproducing system 16 which have been shown in FIG. 1.

The pulse shaper 19 comprises a differentiation circuit 36 consisting of a capacitor C_1 and a resistor R_{11} ; and an amplifier 37 which includes a grounded-emitter transistor Q_9 having its base connected via a diode D_3 of the indicated polarity to the junction 38 of the resistor R_{11} with the capacitor C_1 .

The clock pulse oscillator 11 comprises a relaxation oscillator 39 constructed of a unijunction transistor (or double base diode) Q_{10} having its emitter connected to the collector of the transistor Q_9 as well as to the junction 40 of the frequency control element 12 with a capacitor C_2 series-connected between the positive power source terminal 32P and a grounded negative power source terminal 32N, the conduction path of the unijunction transistor Q_{10} across the first and second bases thereof being connected to the positive and negative power source terminals 32P and 32N via resistors R_{12} and R_{13} respectively; and a flip-flop or frequency divider 41 constructed of two grounded-emitter transistors Q_{11} and Q_{12} each having its base cross-coupled to the other transistor collector via a parallel circuit of a resistor and a capacitor and alternatively rendered conductive by an output from the relaxation oscillator 39.

The operation of the automatic rhythm device according to the invention will now be described with reference to the accompanying drawings.

Firstly, let it be assumed that the switches 20 and 23 are left open and the movable contact 22a of the switch 22 contacts the stationary contact 22b. Then in the stand-by circuit 30, the transistor Q_4 becomes conductive and the transistor Q_5 remains nonconductive. Under this condition, the transistor Q_6 is made conductive by its base bias circuit including the resistor R_7 and the forwardly biased diode D_1 , and in consequence the initial condition of the device represented by the bistable circuit 33 is attained so that the transistor Q_2 is off or nonconducting and the transistor Q_3 is on or conducting.

At this time, the transistor Q_7 is kept conductive by its base breeder circuit including the collector resistor R_4 of the now nonconducting transistor Q_5 , the resistors R_9 and R_8 and the collector-emitter path of the now conducting transistor Q_6 . Accordingly, the collector potential of the transistor Q_7 is substantially equal to the ground potential.

In consequence, the field effect transistor Q_8 is made nonconductive, producing no rhythm sound from the device.

Next, when the engagement of the movable contact 22a of the switch 22 is changed over from the stationary contact 22b to the other contact 22c, the stand-by circuit 30 is brought to a reverse condition to make the transistor Q_5 conductive and the transistor Q_4 nonconductive. Therefore, the transistor Q_7 is rendered nonconductive and in consequence its collector potential is equal to the positive power source potential. As the result, the field effect transistor Q_8 is fired to allow rhythm performance sounds to emanate from the device.

Though, at this time, a differentiating wave consisting of a positive-going component and a negative-going component is generated by the differentiation circuit 36, only the positive-going component is supplied through the diode D_3 and the amplifier 37 to the emitter of the unijunction transistor Q_{10} as the undermentioned external trigger signal. That is, the relaxation oscillator 39 including the unijunction transistor Q_{10} ordinarily generates repetitively a signal having a frequency determined by the charging-discharging time constant derived from the product of the resistance of the frequency control element 12 and the capacitance of the capacitor C_2 .

However, when the external trigger signal is supplied to the emitter of the unijunction transistor Q_{10} , then the transistor Q_{10} is forcibly rendered conductive, causing the relaxation oscillator 39 to be started, regardless of the condition of the transistor Q_{10} .

Thus, the rhythm performance from the device is always initiated in exactly timed relationship with the firing of the field effect transistor Q_8 .

When, under this condition, the reversing switch 20 is closed by the player during performance, then the bistable circuit 33 is set in the reverse condition so that the transistor Q_2 becomes conductive and the transistor Q_3 non-conductive through the now conducting transistor Q_1 , causing the transistor Q_7 to be rendered conductive. As a result, as will be apparent from the above description, the rhythm performance from the device is automatically stopped or terminated. Where, in this case, the clamping switch 23 is kept closed, then the bistable circuit 33 is not brought to the reverse position even if the switch 20 is closed as above-mentioned, thereby continuing the rhythm performance from the device.

On the other hand, when the reversing switch 20 is again closed by the player, with the clamp switch 23 kept open, then the bistable circuit 33 is again brought to the above-mentioned original or initial condition,

causing the rhythm performance from the device to be again started.

When the stand-by switch 22 is brought back to its original state with the movable contact 22a being in contact with the stationary contact 22b, the operation of the device is stopped.

Accordingly, the automatic rhythm device of this invention when incorporated in an electronic musical instrument enables the start and termination of rhythm sounds from the device to be positively and securely controlled.

What is claimed is:

1. In an automatic rhythm device incorporated in an electronic musical instrument of the type including a clock pulse oscillator generating a repetitive pulse train of a predetermined frequency, a multi-stage frequency dividing counter chain cascade connected to said clock pulse oscillator, a rhythm pattern pulse encoding matrix connected to the output of each stage of said counter chain to produce a plurality of sets of required rhythm pattern pulse trains, rhythm selector switches coupled to said encoding matrix, a plurality of rhythm sound sources coupled to said rhythm selector switches and each triggered by at least one rhythm pattern pulse train preselected by said selector switches, and a sound reproducing system coupled to said rhythm sound sources for rendering the triggered rhythm sounds audible, the improvement comprising:

a normally non-conducting gate circuit connected between said rhythm sound sources and said sound reproducing system;

a rhythm start and stop controller including a two-way switch operated during performance of the instrument by a player; and

35 a bistable circuit coupled to said two-way switch, said bistable having two halves which may be set alternatively in reverse positions by operation of said two-way switch, one half output of said bistable causing said gate circuit to conduct and said clock oscillator to be forcibly started.

2. An automatic rhythm device as claimed in claim 1 wherein said rhythm start and stop controller further includes an initial condition setting circuit which is constructed of a normally conducting active circuit element having its conduction path connected in parallel with said one half of said bistable circuit and rendered nonconductive during rhythm performance.

45 3. An automatic rhythm device as claimed in claim 1 wherein said rhythm start and stop controller further includes a normally open switch coupled with said one half output of said bistable circuit and closed while rhythm performance is freely continued.
